 York, N. Y., a corporation of New York

Application April 18, 1933, Serial No. 666,637,
 and in Austria June 16, 1932

9 Claims. (Cl. 179—16)

This invention relates to automatic telephone systems and more particularly to systems in which the various switches are directly responsive to impulses of current. The object of the invention is to provide an efficient and reliable circuit arrangement for directly controlling automatic switches.

It is well known in dial telephone systems that the transmission of dial impulses over long trunks or through one or more repeaters causes distortion which may result in faulty operation of the directly controlled switches used in establishing telephone connections. In the case of multiple repeating, the first impulse of a series is shortened as well as distorted so that this impulse becomes ineffective to operate the selecting mechanism although succeeding impulses are of sufficient length. To correct for distortion it is well known to provide circuit arrangements for correcting all of the impulses; to be fully effective such arrangements are somewhat complicated whereas a more simple arrangement is suitable where only the first impulse of a series is too short to effect the proper response. This invention is an impulse receiving circuit so arranged that the associated selector switch will respond to a very short initial impulse, a part of the second impulse of the incoming train being used for completing the operation of the switch in response to the first impulse. To this end the arrangement comprises a primary impulse relay, the usual release relay and an auxiliary impulse relay, the primary impulse relay remaining deenergized after its release in response to the first impulse until the selector magnet is fully operated even though the opening of the impulse circuit is of a shorter duration. A feature of the invention is an auxiliary impulse relay connected to the impulse circuit after receipt of the initial impulse for operating upon closure of the impulse circuit during the time the switch is responding to the first impulse.

The drawing, which forms a part of this specification, illustrates schematically, a portion of a selecting mechanism arranged in accordance with the features of this invention. Referring to the drawing:

Fig. 1 shows in diagrammatic form a series of impulses;

Fig. 2 represents schematically an impulse responsive selecting mechanism.

The impulse series illustrated in Fig. 1 is one in which the first impulse is too short to effect a proper selective operation while the succeeding impulses are somewhat longer than is required for effecting the proper selective operations. The

selecting mechanism of Fig. 2 is so arranged that part of the time interval occupied by the second impulse of the series illustrated in Fig. 1 is utilized in securing proper operation in response to the short first impulse. All apparatus not essential to a clear and complete description of the invention has been omitted.

Upon seizure of the selecting mechanism of Fig. 2, the line relay 10 operates in a circuit which is not shown. The operation of relay 10 closes a circuit from battery through resistance 14, front contact of relay 10, back contact of relay 13, and through the right winding of relay 11 to ground. Relay 11 operates due to the energization of its right winding and closes a circuit for operating the slow-to-release relay 13. Relay 13 opens the operating circuit through the right winding of relay 11 but relay 11 is held operated by the circuit from battery through resistance 14, front contact of relay 10, left front contact of relay 11, and through both windings of relay 11 in series, to ground. No further action takes place until a series of impulses is received by relay 10. The release of relay 10 in response to the first impulse closes a circuit from battery through the winding of selector magnet 16, right front contact of relay 13, to ground at the right back contact of relay 11. The magnet 16 is thus energized in response to the first impulse. Relay 11 can not reoperate before magnet 16 has fully operated and performed the desired selecting operation in response to the first impulse because its initial operating circuit is open at the outer left contacts of relay 13, the latter relay remaining operated during the temporary release of relay 11 in response to incoming impulses.

When relay 10 reoperates, at the end of the first impulse, a circuit is closed from battery through resistance 14, front contact of relay 10, the left back contact of relay 11, left front contact of relay 13, and through the left winding of relay 12 to ground. Relay 12 is thereby operated closing a circuit from battery through its right winding and front contact, front contact of magnet 16, through the right winding of relay 11 to ground. Relay 11 is reoperated by the energization of its right winding in this circuit thereby closing the circuit through the winding of relay 13, opening the operating circuit through the left winding of relay 12, opening the circuit through the winding of magnet 16 and closing circuits from battery through resistance 14 and the front contact of relay 10, and from battery through resistance 15 and the left front contact of relay 12, through the left front contact and both windings of relay 11.

11 in series, to ground. Relay 11 is thus held operated as long as either of relays 10 and 12 remains operated. Relay 12 remains operated by the circuit through its right winding until magnet 5 16 releases. When magnet 16 releases, relay 12 releases, relay 11 being held by relay 10 if this relay has not again released in response to a second incoming impulse. When relay 10 releases, (or when relay 12 releases, if relay 10 has 10 already received the second impulse before magnet 16 and relay 12 release), relay 11 releases causing the above cycle of operations, as described as occurring in response to the receipt of the first impulse, to be repeated.

15 Although the relay 10 has been described as being responsive to incoming impulses, the front contacts of this relay may also be considered as representing the interrupter contacts of an impulse sender such as a dial. Irrespective of 20 whether these contacts are directly or indirectly responsive to the operation of an impulse sender, the arrangement of relays 11, 12 and 13 is effective to insure the proper operation of the selecting mechanism represented by magnet 16, 25 the circuit for magnet 16 being closed until its armature is fully attracted and opened until the armature has been released irrespective of the length of the impulse received.

30 Although disclosed in an arrangement for directly controlling an impulse responsive selecting mechanism, the invention is also applicable to impulse repeaters generally. For use as a repeater, the magnet 16 of Fig. 2 becomes an impulse repeating relay, an additional set of normally closed contacts being connected by an additional front contact of the slow-to-release relay 13 across the conductors over which the impulses are to be repeated.

35 What is claimed is:

40 1. In combination, a magnet, an impulse receiving circuit, a first relay energized over said circuit, an auxiliary relay, means effective upon the release of said first relay in response to the opening of said circuit for energizing said magnet, 45 means effective upon the release of said first relay for disconnecting said first relay from said circuit and for connecting said auxiliary relay to said circuit, and means rendered effective by the operation of said auxiliary relay over said 50 circuit and the complete operation of said magnet for reoperating said first relay.

55 2. In an impulse receiver, a first relay responsive to incoming impulses, a magnet for operation in accordance with incoming impulses, a second relay operated in response to the operation of said first relay, the operating circuit for said magnet being closed by the release and opened by the operation of said second relay, a third relay, an operating circuit for said third relay closed by the release of said second relay, and a circuit for holding said third relay and reoperating said second relay, said last mentioned 60 circuit being closed by the operation and opened by the release of said magnet.

65 3. In an impulse receiver, a first relay responsive to incoming impulses, a magnet for operation in accordance with incoming impulses, a second relay operated in response to the operation of said first relay, the operating circuit for said magnet being closed by the release and opened by the operation of said second relay, a third relay, an operating circuit for said third relay closed by the release of said second relay, a circuit for holding 70 said third relay and reoperating said second relay independently of said first relay, and a cir-

cuit for holding said second relay after its re-operation independently of said first relay, said last mentioned circuit being opened in response to the release of said magnet.

4. In combination, an impulse receiving relay, 80 a magnet for operation in accordance with impulses received by said relay, a second relay initially operated in response to the operation of said impulse receiving relay, the operating circuit for said magnet being closed by each release and opened by the succeeding reoperation of said second relay, a third relay, the operating circuit for said third relay being under the joint control of said first and second relays, and a circuit for holding said third relay and reoperating said 85 second relay, said last mentioned circuit being under the sole control of said magnet.

5. In combination, an impulse receiving relay, 90 a magnet for operation in accordance with impulses received by said relay, and means for correcting said impulses to insure the proper response of said magnet, said means comprising a first relay for opening and closing the operating circuit of said magnet, the initial operation and release of said first relay being controlled by said 95 impulse receiving relay, and a second relay for controlling the reoperation of said first relay, the operating circuit for said second relay being dependent upon the complete operation of said magnet and the reoperation of said impulse receiving relay.

6. In combination, an impulse receiving relay, 100 a magnet for operation in accordance with impulses received by said relay, a first auxiliary relay for closing and opening the operating circuit for said magnet, a second auxiliary relay, and circuit connections such that the initial operation and release of said impulse receiving relay effects the initial operation and release of said 105 first auxiliary relay, each succeeding operation of said impulse receiving relay effects the operation of said second auxiliary relay without effecting the operation of said first auxiliary relay, the operation of said second auxiliary relay effects the reoperation of said first auxiliary relay, 110 and each succeeding release of said impulse receiving relay effects the release of said first auxiliary relay.

7. In combination, an impulse receiving relay, 115 a first auxiliary relay, a second auxiliary relay, 120 the operation of said first auxiliary relay being effected by the initial operation of said impulse receiving relay, and the initial release of said first auxiliary relay being effected by the release of said 125 impulse receiving relay upon receipt of the first impulse of a series, a magnet for operation in accordance with impulses received by said impulse receiving relay, a circuit closed by the release of said first auxiliary relay for operating said magnet, a circuit closed by the release of 130 said first auxiliary relay and the reoperation of said impulse receiving relay after the first impulse for operating said second auxiliary relay, means including said second auxiliary relay for preventing the reoperation of said first auxiliary 135 relay until said magnet has operated in response to the first impulse, and means for preventing the second release of said first auxiliary relay until said magnet has released.

8. In combination, an impulse receiving relay, 140 a first auxiliary relay, a second auxiliary relay, 145 the operation of said first auxiliary relay being effected by the initial operation of said impulse receiving relay, and the initial release of said first auxiliary relay being effected by the release of 150

- 20 said impulse receiving relay upon receipt of the first impulse of a series, a magnet for operation in accordance with impulses received by said impulse receiving relay, a circuit closed by the release of said first auxiliary relay for operating said magnet, a circuit closed by the release of said first auxiliary relay and the reoperation of said impulse receiving relay after the first impulse for operating said second auxiliary relay, means including said second auxiliary relay for preventing the reoperation of said first auxiliary relay until said magnet has operated in response to the first impulse, and means for holding said first auxiliary relay after its reoperation until said magnet has released.
- 25 9. In combination, a first relay, a circuit for operating said first relay, impulse contacts included in said circuit, means for alternately opening and closing said impulse contacts, a slow-to-
- 30 release relay operated in response to the operation of said first relay, the operation of said slow-to-release relay being effective to open said circuit, a circuit controlled exclusively by said impulse contacts for holding said first relay, a magnet for operation in response to the opening of said impulse contacts, an operating circuit for said magnet closed by the operation of said slow-to-release relay and release of said first relay, an auxiliary relay, an operating circuit for said auxiliary relay closed by the operation of said slow-to-release relay and release of said first relay, said operating circuit including said impulse contacts, a circuit closed by the operation of said magnet for holding said auxiliary relay and for reoperating said first relay, and a circuit controlled exclusively by said auxiliary relay for holding said first relay after its reoperation.
